UNITED STATES PATENT OFFICE.

WILLIAM REES HARLEY, OF LOS ANGELES, CALIFORNIA.

DOUBLE-SWIVEL HANGER AND SUPPORT FOR PUNCHING BAGS AND THE LIKE.

Application filed May 8, 1923. Serial No. 637,431.

This invention relates to means for suspending and supporting such objects as punching bags, hammocks, chairs, and swings; and an object of this invention is to provide a compact appliance with two swivelling connections, each having universal and independent movement, and both being adapted to quickly respond to movement imparted to the suspended object.

10 An object of the invention is simplicity in construction and high efficiency in operation.

An object of this invention is to provide a simple and novel non-stretchable punching bag support that will not decrease the speed 15 of the punching bag.

Another object is to provide a swivel that is easy to adjust and assemble.

The type of support now generally used for punching bags comprises a swivel and a 20 rope connecting the bag to the swivel, and I have discovered that after a short use of the punching bag the rope will stretch, and thereby suspend the bag at a farther distance from the board commonly used in combination 25 with a punching bag. By thus increasing the length of suspension due to the rope stretching the usual synchronism obtained with the bag suspended the correct distance is lost, and in order to readjust the bag new 30 pieces of rope are required with the result that they soon stretch and have to be replaced.

An object of this invention is to provide a novel punching bag support which will 35 not stretch with use.

Another object is to provide for punching bags a support which is not likely to break after considerable use.

40 Other objects, advantages and features of invention may appear from the accompanying drawing, the subjoined detail description and the appended claims.

The accompanying drawing illustrates the invention.

45 Figure 1 is a side elevation of a swivel or support constructed in accordance with this invention and shown supporting a punching bag.

Fig. 2 is an enlarged fragmental section 50 on line α^2 , Fig. 1.

Fig. 3 is a fragmental section on line α^3 , 55 Fig. 2.

Fig. 4 is an elevational detail of the spherical segment or bushing detached from the swivel.

Fig. 5 is a section on line α^5 , Fig. 4.

Fig. 6 is a detail of the hanger detached from the swivel; and showing the split threaded shank open to receive a strap of a punching bag, swing or hammock.

Fig. 7 is a view of the hanger with its shank inserted through an opening in the spherical segment or bushing and in a position where the parts of the split shank are forced together and held so that a nut can 65 be screwed on the shank.

Fig. 8 is a grouped view of the swivel nut showing both the ends and a side view.

The support or swivel 1 comprises a base plate 2 that is secured by screws 3 to an 70 overhead support 4; and the base plate 2 is provided with a threaded opening 5 into which is screwed one end of a circular extension or cylinder 6 which may be knurled, if desired, and that depends downward from 75 the base plate 2. The end of said cylinder 6, opposite the base plate is contracted to provide an internal seat 7 which supports a hollow spherical segment or bushing 8.

The bushing 8 is perforated at 9 to form 80 an opening opposite the open upper end 10. A bag supporting member comprises at one end a split threaded shank 11 and at its other end a metal ring hanger 12. The shank 11 is extended through the perforation 9 and on this shank is threaded a swivel nut 13 having a convex surface a , that seats on the inner surface 14 of the bushing 8 adjacent the opening 9, and adjustably retains 85 hanger in mounted position.

The nut 13 is provided with a transverse hole 13' that is adapted to coincide with one of the spaced holes 11' in the shank 11 and to receive a cotter pin 15 which prevents accidental displacement of the nut 13.

90 The shank 11 is of slightly less diameter than the opening at 9 so that it can be easily inserted into the perforation 9. The shank 11 is thereby loosely mounted through the perforation 9 and is permitted to swing a short distance before it contacts with and moves the bushing 8; by which construction, combination and arrangement of the parts a double swivel movement is accomplished. That is, when swinging movement is imparted to the hanger 12 it will first move 100 the swivel nut on its bearing or contacting surface until the shank 11 contacts with the bushing 8, after which, the second swivel action begins and the bushing 8 moves in the seat 7.

105 Preferably the hanger 12 is formed of

spring metal so that the halves of the split shank 11 will be normally spaced apart or separated as shown in Fig. 6 so that a normally closed strap loop 16 of a punching bag 17 or other article to be supported can be slipped through the space and thus mounted on the ring portion of the hanger and be secured thereon so that it cannot escape. In other words, when the closed strap 10 or supporting loop 16 is fitted to the ring of hanger 12 and the halves of shank 11 closed and secured by nut 13 there is no way for the punching bag to escape from the hanger except for the strap to break.

15 To facilitate the attachment of nut 13 to the split shank 11 the hanger 12 is forced upward through the hole 9 in bushing 8 until the halves of the shank are forced together in close contact as illustrated in Fig. 20 7 by action of the curved surfaces 12' against the walls forming the perforation. The shank is held in this position until the nut is screwed onto the shank until the hole 13' coincides with the selected hole 11', after 25 which the cotter pin 15 is inserted through such coinciding holes to retain the nut on the shank 11. To facilitate the insertion and withdrawal of the cotter pin in the holes 11' and 13' a slot 18 may be cut in the wall 30 of the bushing 8.

In use, the parts of the hanger are assembled and secured to a support as shown after which the hanger is free to swing or spin when the object it supports such as the 35 punching bag is removed; and the parts are so constructed and arranged that the hanger may spin and swing on the swivel nut 13 and also have additional play or movement by means of the swivel bushing in which the 40 swivel nut is supported.

An advantage gained by use of a swivel constructed as above set forth for supporting a punching bag is that the strap loop 16 is supported in the ring 12, which presents 45 a rounded surface for the strap to engage and slide upon and also presents a surface that acts evenly as a resistance to action of the bag without any lost motion.

Another advantage is that when the 50 hanger is used as a support for a punching bag the speed of the bag is greatly increased over metal punching bag supports heretofore known. This is made possible by the construction and arrangement of parts in 55 which the strap loop 16 will slide upon the circle 12 without lost motion and the convex surface *a* of the nut 13 will swivel on the inner surface 14 of the bushing 8 which in turn is swivelly mounted in the cylinder 6.

60 I claim.

1. A punching bag support comprising a base plate having a threaded opening; a cylinder contracted at one end and threaded into said opening at its other end; a hollow 65 spherical segment seated in said contracted

end and having a perforation therein; a supporting member having at one end a ring adapted to receive the strap loop of a punching bag and having at its other end a threaded shank that loosely extends through 70 the perforation in said segment; and a nut threaded on said shank and adapted to adjustably retain said support in position, said nut having a convex surface seated on the inner surface of said segment. 75

2. A hanger having a shank; a swivel nut detachably and adjustably attached to said shank; a hollow bushing in which said shank and nut are movably mounted; a cylinder having a seat in which said bushing 80 is mounted; and a support for said cylinder.

3. A hanger having a split shank adapted to have the strap loop of a punching bag slipped through the space between the halves of the split shank when the hanger is detached; a swivel nut detachably and adjustably attached to said shank; a hollow bushing in which said shank and nut are movably mounted; a cylinder having a seat in which said bushing is movably mounted; 90 and a support for said cylinder.

4. A hanger having a split threaded shank adapted to have the strap loop of a punching bag slipped through the space between the halves of the split shank when the 95 hanger is detached; a swivel nut threaded on said shank; means for holding said nut in a fixed predetermined position on said shank; a hollow spherical segment in which said nut is mounted for swivelling movement; a cylinder having a seat in which said bushing is swivelly mounted; and a support for said cylinder. 100

5. A punching bag support comprising a base plate adapted to be secured to a support; a circular extension depending from and detachably connected to said base plate and being contracted at its lower end; a hollow spherical segment supported by said contracted end and having a perforation therein; a hanger having a shank loosely extending through said perforation and adapted to swivel therein; and means adjustably mounted on said shank to support said hanger. 105 110

6. The combination with an article to be supported having a supporting loop; of a base plate having a threaded opening; a cylinder contracted at one end and threaded into said opening at its other end; a hollow 115 spherical segment seated in said contracted end and having a perforation therein; a hanger having a split shank normally spaced apart to receive said loop, said shank extending through said perforation; and means seated on the inner surface of the hollow segment to retain said hanger in mounted position. 120

7. A punching bag support comprising a bag supporting member having at one end a 130

threaded shank and at its other end a ring adapted to receive the strap loop of a punching bag; a hollow bushing in which said shank is movably and loosely mounted; a nut threaded on said shank and having a surface slidably seated on the inner surface of said bushing; a cylinder in which said bushing is mounted; and a support for said cylinder.

10 8. A punching bag support comprising a bag supporting member having at one end a ring adapted to receive the strap loop of a punching bag and having at its other end a threaded split shank adapted to have the

strap loop of a punching bag slipped 15 through the space between the halves of the split shank when the hanger is detached; a hollow bushing having a perforation through which said split shank extends; a nut threaded onto said shank and adapted 20 to adjustably secure said ring relative to said bushing; and a support for said bushing.

In testimony whereof, I have hereunto set my hand at Los Angeles, California, this 3rd 25 day of May, 1923.

WILLIAM REES HARLEY.
